[57] CLAIM

The ornamental design for a garden marker, substantially as shown and described.

DESCRIPTION

FIG. 1 is a front elevational view of a garden marker showing my new design;

FIG. 2 is a side elevational view of the right side of the garden marker of FIG. 1; the left side being a mirror image of FIG. 2;

FIG. 3 is a top plan view of FIG. 1;

FIG. 4 is a bottom plan view of FIG. 1;

FIG. 5 is an enlarged sectional view taken along the line 5—5 of FIG. 1;

FIG. 6 is an enlarged sectional view taken along the line 6—6 of FIG. 1; and

FIG. 7 is a rear elevational view in reduced scale of the garden marker of FIG. 1.

FIG. 1

FIG. 2
